UNITED STATES PATENT OFFICE.

ENGELBERT JAWOREK, OF CRESCENT CITY, CALIFORNIA.

DUMPING-CAR.

1,115,547.

Specification of Letters Patent.

Patented Nov. 3, 1914.

Application filed June 15, 1914. Serial No. 845,168.

To all whom it may concern:

Be it known that I, ENGELBERT JAWOREK, a citizen of Austria, residing at Crescent City, in the county of Del Norte and State of California, have invented certain new and useful Improvements in Dumping-Cars, of which the following is a specification.

This invention relates to improvements in dumping cars and its object is to provide a new and improved device of this class that is simple and durable in construction and that is designed to discharge the load to either side of the car.

Another object is to provide a car in which the box or body may be rotated upon the carriage frame without danger of toppling off said frame.

With the foregoing and other objects in view the invention consists in the combination and arrangement of parts to be herein-after described fully in the following specification, pointed out in the claims and illustrated in the accompanying drawings which form a part of said specification and in which—

Figure 1 is a side elevation of my improved dumping car. Fig. 2 is a cross section taken on line 2—2 of Fig. 1. Fig. 3 is a fragmentary end view. Fig. 4 is a cross section taken on line 4—4 of Fig. 3. Fig. 5 is a section taken on line 5—5 of Fig. 2. Fig. 6 is a section taken on line 6—6 of Fig. 5. Fig. 7 is a detail.

Like reference characters indicate corresponding parts throughout the several views.

The reference numeral 1, designates the carriage frame of my dumping car which is provided with the channel iron 2 and upon said carriage a turn table 3 is disposed through which the king bolt 4 passes that serves as a pivot for said table and secures the same to the carriage. Upon the ends of the carriage frame, end plates 5, 6 are secured each of which carries a stop pin 7 and a bolt 8 and said bolts carry U-shaped tongues, 9, 9 adapted to telescope into the approximately U-shaped pockets 10, 10 which are disposed upon bolts 11, 11 carried by the car floor 12 which is bolted as at 13 to the top of the turn table, and which rotates therewith. A spring-pressed pin 14 carried by each pocket 10 normally engages the tongue 9 to retain said members in mutual engagement and to prevent accidental rotation of the table 3. To permit

disengagement of the tongues 9 and pockets 10 the pins 14 are withdrawn from the tongues when the floor 12 and table 3 may be manually moved about the pivot or bolt 4. To prevent the floor 12 from moving too far off the carriage frame and possibly toppling therefrom each pocket 10 is formed with a lug 15 adapted for engagement with the stop pin 7 when said floor is turned at a certain angle with the carriage frame.

Upon the floor 12 the sides 16 of the car are disposed which are formed with hinged doors 17 and said sides, further, are provided with brackets 18 in which door holders 19 are pivotally mounted and which may be used to prop the doors open as shown in Fig. 2 of the drawings. To the car sills 20 keepers 21 are secured which may be engaged by levers 22 carried by the doors 17 to retain them in closed position. Within the car upon the floor 12 a false floor composed of sections 23, 24 is disposed, said sections being formed with hinges 25 through which a shaft 26 extends that runs from end to end of the car and is journaled in the ends thereof. To each end of the car a plate 27 is secured formed with a vertical slot 28 along one lateral edge and through this slotted portion the end shaft 26 extends and carries a pinion 29 that works over a vertical rack 30 disposed adjacent plate 27 upon the car. A pin 31 removably disposed in one of the bores 32 of plate 27 is adapted to engage the pinion 29 to retain it in adjusted position with relation to the rack 30. Each end of the shaft 26 is provided with a crank 33 by which it is rotated.

To give the false floor of the car a pitch so that the load will readily slide therefrom, when the doors are open, the cranks 33 are rotated in a direction to cause the pinions 29 to ride upward over the racks 30, taking with them the shaft 26 and the floor sections. By placing the pins 31 in engagement with the pinions in their adjusted position they will be secured in such position. The car may now be loaded.

What is claimed is:—

1. In a dumping car comprising a carriage frame and a turn table disposed thereupon, a floor carried by said turn table, end plates carried by said carriage frame, telescoping couplings carried by said end plates and floor and means carried by said end plates in the plane of movement of said couplings whereby the movement of the tele-

scoping coupling sections with relation to each other is limited.

2. In a dumping car comprising a carriage frame and a turn table disposed thereupon, a floor carried by said turn table, end plates carried by said carriage frame, pockets carried by said floor, tongues carried by said end plates for releasable locking engagement with said pockets and 10 means connecting said pockets and end plates whereby the movement of the former

members with relation to the latter is limited.

In testimony that I claim the foregoing as my own I have hereto affixed my signature in the presence of two subscribing witnesses.

ENGELBERT JAWOREK.
